United States Patent Office.

THOMAS SMITH, OF CALIFORNIA, MISSOURI.

Letters Patent No. 81,696, dated September 1, 1868; antedated August 29, 1868.

IMPROVEMENT IN SELF-ACTING WAGON-BRAKE.

The Schedule referred to in these Letters Patent and making part of the same.

TO ALL WHOM IT MAY CONCERN:

Be it known that I, THOMAS SMITH, of California, in the county of Moniteau, and State of Missouri, have invented a new and improved Self-Acting Wagon-Brake; and I do hereby declare the following to be a full, clear, and exact description of the same, sufficient to enable those skilled in the art to which my invention appertains to make use of it, reference being had to the accompanying drawings, forming part of this specification, and in which—

Figure 1 is a side elevation, and

Figure 2 a top view of my invention.

In this invention the friction-blocks are adjustable in order to accommodate them to different wheels, and are directly attached to and supported by the springs of the brake. The apparatus is also made adjustable to horses of different sizes.

In the drawings, A represents the wheels; B, the axle; C, the tongue; D D, braces attached to strengthen the tongue and provide a support for the brakes; and E a stout, flat spring attached at its middle to a bar, F, which connects the rear ends of the braces D D. The spring E is made long enough to extend from wheel to wheel, and to its ends are fixed the friction-blocks e e, which are applied to the wheels to retard their motion. These blocks may be either rigidly attached to the springs, or they may be pivoted to a clasp or slide, G, which is made adjustable along the spring by means of a slot and set-screw, s, to accommodate the block to differently-constructed wheels. The blocks e e being pivoted to the clasp or slide G, will accommodate themselves to the position of the rim against which they operate, always presenting their whole length fairly against the wheel.

The spring E holds the blocks close to but not in contact with the tire of the wheel. In order to apply the brake to the wheels, I connect the spring by rods h h, from a point near each end to a rod, I, which extends the whole length of the tongue, lying under it and sliding longitudinally in sockets i i, provided for the purpose. The forward end of this rod I connect with the neck-yoke J by means of a cord or chain, k, passing over a pulley, m, in the end of the tongue. By this means, whenever the neck-yoke is thrown back, as in backing, or holding back when going down-hill, the rod I is drawn forward and the brakes applied.

A ring, r, attached to the neck-yoke, passes around the tongue, and rests against a pin, t, when the yoke is thrown back, for the purpose of backing or holding back the carriage. This pin may be adjusted in different positions along the tongue by means of a series of holes, v v v, provided for the purpose, in order to accommodate the apparatus to horses of different sizes.

The whole device forms the most simple, durable, and effective apparatus for the purpose which has yet been brought into use. It has been thoroughly tested, and found to be in every respect superior to the old form of brake. It can be attached at little expense to any kind of carriage, and its adjustability gives it a decided advantage over those brakes which can only be used in connection with axles of the same length or wheels of the same form.

Having thus described my invention, what I claim as new, and desire to secure by Letters Patent, is—

The self-acting wagon-brake, composed of the block e, pivoted to the adjustable slide G, which is itself directly attached to the spring E, and operated by the rods h and I and yoke J, when the parts referred to are constructed as described, and combined and arranged in the manner and for the purposes specified.

To the above specification of my improvement I have signed my hand, this 16th day of January, 1868.

THOMAS SMITH.
